UNITED STATES PATENT OFFICE.

DARIUS PARKHURST, OF ST. LOUIS, MISSOURI, ASSIGNOR OF ONE-HALF
TO GEORGE H. KNIGHT, OF SAME PLACE.

HEAD-BLOCK FOR SAW-MILLS.

SPECIFICATION forming part of Letters Patent No. 267,923, dated November 21, 1882.

Application filed August 2, 1882. (No model.)

To all whom it may concern:

Be it known that I, DARIUS PARKHURST, of the city of St. Louis, in the State of Missouri, have invented a certain new and useful Improvement in Friction-Brakes for Saw-Mill Head-Blocks, of which the following is a full, clear, and exact description, reference being had to the accompanying drawings, forming part of this specification, and in which—

10 Figure 1 is a side elevation; Fig. 2, a detail side view, and Fig. 3 an enlarged detail perspective view.

The present invention relates to an improvement on Letters Patent No. 257,060, granted 15 to myself and assignee, April 25, 1882; and it consists in a device to prevent any possibility of the main wheel turning backward when at work, but not interfering with its free forward movement, as more fully set forth hereinafter.

20 Referring to the drawings, A represents the frame; B, the combined index, ratchet, and brake-wheel; C, the index-arm; D, the operating-lever; E, the reversible pawl; F, the strap-brake; G, the brake-lever, and H H the standards to which the brake-lever is pivoted. All these parts are fully shown and described 25 in the patent referred to, and therefore need no further description, either as to their formation or operation, here.

30 In practice it has been found that when both the operating-lever and the index-arm are brought back at the same time, when the machine is at work, the pressure of the pawl against the ratchet-wheel as it slips over the teeth is liable to cause a slight backward movement of the wheel, which would prevent the index engaging the proper notch. As before stated, this difficulty is only liable to occur when both the index and the lever are 40 brought back at the same time, for if the lever

is brought back first, while the index is still engaging the notch I of the arm J, the wheel cannot possibly turn, for, as stated in the said former patent, the index engages this notch I and the wheel at the same time. It was at first proposed to prevent this liability of the wheel turning back by slightly applying the strap-brake, and the only objection to this manner of meeting the difficulty is that a slight pressure is upon the wheel continually, not only 45 when the index and lever are brought back, but also when the wheel is turning forward. Now, to prevent any liability of the wheel turning when the lever and index are thus brought back together, and at the same time not have 50 any unnecessary friction when the wheel is moved forward, is the object of the present invention; and it is accomplished by pivoting to the upper ends of the standards H a friction-block, L, which can be thrown over 55 into engagement with the face of the wheel, as shown, or thrown back out of engagement therewith. As it is a less distance from the pivot to the face of the wheel than from the pivot to the part of the block that bears against 60 the wheel, it will be seen that when the block is against the wheel it will be impossible for the latter to turn back, while its free forward movement is not in the least interfered with.

I claim—

In a saw-mill head-block, the combination of combined index, ratchet, and brake-wheel B, with horizontal frame A, standards H H, formed on said frame, and friction-block L, hinged between said standards, as set forth. 75

DARIUS PARKHURST.
